US00D830123S

(12) **United States Design Patent** (10) **Patent No.:** **US D830,123 S**
(45) **Date of Patent:** **** Oct. 9, 2018**

(54) **DISPENSER**

(71) Applicant: **YETI Coolers, LLC**, Austin, TX (US)

(72) Inventors: **Roy Joseph Seiders**, Austin, TX (US); **James William Sonntag**, Austin, TX (US); **Christopher Mall Keller**, Austin, TX (US); **Steve Charles Nichols**, Austin, TX (US); **Martin Patrick Vespo**, Austin, TX (US)

(73) Assignee: **YETI Coolers, LLC**, Austin, TX (US)

(**) Term: **15 Years**

(21) Appl. No.: **29/610,460**

(22) Filed: **Jul. 12, 2017**

(51) LOC (11) Cl. **07-99**

(52) U.S. Cl. **D7/398**
USPC ....

(58) **Field of Classification Search**

USPC D7/398, 397; D23/263, 262, 266, 259, D23/213, 226, 225; 137/318, 89, 614.11, 137/170.2; 222/496, 504, 385, 394, 213, 222/94, 21, 163, 402.22, 517, 506, 207, 222/145.1; 264/163

CPC B29C 53/76; B29C 66/52241; F16L 47/32; F16L 41/021

CLAIM

The ornamental design for a dispenser, as shown and described.

DESCRIPTION

FIG. 1 is a top, front, right perspective view of a dispenser showing our new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The broken lines shown in the figures are for the purpose of illustrating portions of the dispenser and form no part of the claimed design.

1 Claim, 7 Drawing Sheets
